UNITED STATES PATENT OFFICE.

NATHAN H. ADAMS, OF SCHENECTADY, NEW YORK, ASSIGNOR TO GENERAL ELECTRIC COMPANY, A CORPORATION OF NEW YORK.

THERMOELECTRIC GENERATOR.

Application filed March 31, 1925. Serial No. 19,733.

This invention relates to improvements in thermo-electric generators, and more particularly to an arrangement for heating the hot junctions of the thermopiles comprising such generators.

Thermopiles heretofore have been constructed with little or no regard to thermal efficiency. A large portion of the heat input inevitably was wasted without having been 10 conveyed to the hot junction of the thermopile. Furthermore, the construction ordinarily was such that even the heat actually conveyed to the hot junction was in large 15 part wastefully conducted away or otherwise dissipated.

I have provided a thermopile of high thermal efficiency and as in accordance with the hereinafter described form of my invention an electric source of heat is utilized, this 20 high thermal efficiency is of added importance to provide not only an economical device but also a device in which heater is not operated at an excessively high temperature and hence will have a commercially long 25 life.

With these objects in view I have provided a construction and organization in a thermopile which gives high thermal efficiency.

In carrying my invention into effect I provide two thermopiles, each having a slot or a groove in the junctions to be heated. These junctions I shall hereinafter designate as hot junctions. The thermopiles are arranged in abutting relation so that the grooves will form a central cavity. Within this central cavity or opening I place a heater element which is electrically insulated from the thermopiles, and which is of substantially the same dimensions as the opening so that the heater will fit snugly therein. As a means for further confining the heat to the hot junction, I provide a heat conserving device comprising a hollow alundum cylinder which substantially surrounds the hot junctions and heater. The space between the cylinder and the thermopile may be filled with any well known heat insulating means such as asbestos wool or the like. By means of this arrangement a relatively large heat receiving surface is obtained; the heat is delivered directly to the hot junctions, and heat losses are reduced to a minimum.

The novel features which I believe to be characteristic of my invention are set forth

with particularity in the appended claims. 55 My invention itself, however, both as to its organization and method of operation, will best be understood by reference to the following description taken in connection with the following drawing in which Fig. 1 60 shows a perspective view of one form of thermo-electric generator of the type shown in the copending application of Truman S. Fuller, Serial No. 3,199, filed January 17, 1925; Fig. 2 shows a perspective view of the 65 preferred embodiment of my invention; Fig. 3 is a longitudinal central section of the device shown in Fig. 2, the heater being shown partially in elevation; Fig. 4 is an exploded view showing the particular type of thermo- 70 electric units and heater element used in connection with the device disclosed in Fig. 2; Fig. 5 is a cross sectional view of one form of heater.

Referring particularly to Figs. 3 and 4 75 of the drawing I have designated two oppositely positioned thermopiles as 1 and 2, each thermopile comprising a structure built up of a number of interconnected thermopiles made of dissimilar metals. The alternate 80 sheets of metal forming the thermocouples are united on their flat surfaces along their edges without bending or folding to form an integral zigzag strip with the hot junctions in alignment, as set forth in my co-pending application Serial #19,732 filed March 31, 1925. Insulating material is inserted between the unlike members of the thermopile and the whole compressed into a 85 compact form.

In order efficiently to heat the hot junctions of each thermopile, and at the same time retard the passage of heat from the hot junctions to the cold junctions, I provide each thermopile with a projecting portion 90 having a head portion 4 in close relation with a heater, and a reduced connecting portion 3. The head portion 4, which includes the hot junctions of the thermopile, is of relatively small mass compared with the 95 main body portion of the thermopile, and is provided with a groove 5. The two thermopiles 1 and 2 are arranged in abutting relation to form a central cavity and are separated from each other at their hot junctions by thin flanged electrically insulating material 6, such as mica. A heater 7 is placed within the central cavity, the dimen- 100 105

sions of the cavity and heater being substantially equal so that a very snug fit is obtained.

In providing a reduced connecting portion 3 to retard the flow of heat between the head and main body portions, it is necessary to consider the total internal resistance of the thermopile since a thermo-electric generator operates at its highest efficiency

10 when the internal resistance of the generator is substantially equal to the external resistance of the load circuit supplied by the generator. In the present case I so proportion the connecting portion 3 that while it has a relatively small cross section compared with the heat receiving surface and therefore serves to retard the flow of heat to the cold junctions, yet the resistance of the pile is not increased beyond a definite amount.

15 20 In this manner, while a maximum amount of heating surface is obtained the passage of heat toward the cold junctions is retarded without undue increase of the resistance in the pile. In order to further retain the heat about the hot junctions I may provide a cylindrical member 8 of alundum which is slotted as shown at 9 and 10. The slots enable the cylinder to slide over the narrow portions 3 of the thermopiles.

25 30 With a thermopile of the construction shown in Fig. 4 it is desirable to provide cooling means in connection with the main body portion of the pile, and I have shown in Figs. 2 and 3 one arrangement whereby efficient cooling may be obtained. The particular combination of cooling fins and thermopiles shown in these figures forms the subject matter of the copending application Serial No. 19,685 of Truman S. Fuller and

35 40 Nathan H. Adams, filed March 31, 1925. The cooling means comprises a plurality of thin U shaped members 11 of aluminum, or other suitable metal, within which the thermopiles fit snugly. The vertical portions of the U are made relatively wide in order to obtain good radiation. Sections of mica or similar insulating material 12 and 13 separate the bottom and outer end of each thermopile from the cooling means and end plates 14 respectively, while similar sheets of insulating material, not shown, separate the sides of the thermopile from the sides of the cooling means.

45 50 55 Each U shaped cooling member is spaced from an adjacent member by U shaped aluminum spacing means 15 having relatively narrow vertical portions. Two I shaped end plates 14 and 16 which may be of brass or a similar material cooperate with spacing blocks 17 and screws 18 and serve to clamp the upper portions of the cooling and spacing means in position. Bolts 19 extend through the lower ends of the spacing means 15 and cooling members 11, and serve to clamp them between end plates 14 and 16.

A bolt 20 cooperates with spacing blocks 17 and clamps the cooling means against each side of the respective thermopiles.

The vertical portion of each end plate 14 and 16 is slotted. The slot in member 16 is substantially the width of the thermopile while that in member 14 is narrow as shown at 21 and is provided with enlarged upper and lower openings 22 and 23. A metal plate 24 fits within the upper enlarged opening and is provided with grooves 25 near each end thereof which cooperate with the upper horizontal portion of end plates 14 and 16, as shown in Figs. 2 and 3, to prevent any longitudinal movement of plate 24. A plate 26 fits beneath plate 24 and is engaged by a screw 27 which serves to exert pressure on plate 26 and thus compress the thermopile. Conducting members 28 to 31 inclusive extend through the upper and lower enlarged openings in the end plates and into contact with the top and bottom members of the respective piles. The conducting members are insulated from portions of the thermo-electric generator, other than the top and bottom members of each thermopile.

When the heater 7 is placed between the two units of the thermo-generator, as shown in Fig. 3, bolts 32 are then inserted through openings in each of the end plates 14 and 16 and the two units are secured in position by means of the nuts 33. Springs 34 surround each bolt 32 between end plates 15, and serve to urge the thermal units apart when the nuts 33 are unscrewed. The terminals of the two thermopiles may be connected in any suitable manner to place the piles in series or in parallel as desired.

The heater 7 comprises a threaded insulating core 41 of soapstone or the like. The ends of the core are reduced in diameter and provided with nickel or similar metallic ferrules 35. The heater wire is wound in the groove on the core and over a portion of the nickel ferrules as shown in Fig. 5. The terminals of the winding are spot welded to the ferrules. I have found that, unless several turns of the heater wire are in contact with a relatively large conducting surface, the heater wire will burn out at its point of attachment to the conducting surface. For this reason I have continued the coil winding at each end to cover a comparatively large portion of the nickel ferrules. It is desirable, of course, to obtain close contact between the heater and heat receiving surface, and in order to obtain such contact the heater should have a smooth outer surface. By proportioning the external diameter of the ferrules so that the external surface of the ferrules will be in alignment with the bottom of the threaded portion of the core, I obtain an arrangement whereby the windings of the heater

coil will be of substantially uniform diameter throughout their entire extent, and in this manner give a smooth outer surface to the heater unit.

In the form of heater as shown in Fig. 5 I extend one of the leads through the insulating core as shown at 36 and provide one of the ferrules with a lug 37 carrying an extension 38. The two terminals of the heater wire as thus formed may be used in connection with a plug which may be attached to any electric light socket.

Like references are used in Figs. 1 and 4 to indicate like parts. In the device shown in Fig. 1, cooling of the cold junctions is effected by providing the main body portion of the individual members of the pile with a comparatively large area rather than by means of cooling fins. An insulated heater 39, substantially rectangular in cross section, fits snugly within the slots 5 in the hot junctions, and insulating strips 40 are inserted between the opposed thermopiles. If desired a heat conserving cylinder 8 may be employed to surround the hot junctions as in Fig. 4.

While I have shown and described the preferred embodiment of my invention it is clear that many modifications thereof may be made without departing from the scope of my invention as set forth in the appended claims.

What I claim as new and desire to secure by Letters Patent of the United States is:

1. A thermopile comprising a plurality of thermo-electric couples, the elements of said couples being arranged substantially parallel to one another, each of said couples having at one end thereof a recess adapted to receive a heater.

2. A thermo-electric unit including a main body portion and a projecting portion, said projecting portion having a groove adapted to receive a heater unit.

3. A thermo-electric unit including a main body portion and a projecting portion having a groove, a heater element within said groove, and an electrical insulator between said heater and projecting portion.

4. A thermo-electric unit comprising a main body portion and a head portion having a groove, a heater in said groove and a reduced portion connecting said head and main body portions.

5. A thermopile comprising a main body portion and a head portion shaped to partially enclose a heater element, and a reduced portion connecting said head and body portions.

6. A thermopile comprising a main body portion of relatively large mass, and a head portion of relatively small mass, and a reduced portion connecting said head and main body portions, said head portion including a series of aligned hot junctions, and

having a heat receiving surface greater than the cross section of said reduced portion.

7. A thermo-electric unit comprising two oppositely disposed thermopiles, each thermopile comprising a series of flat parallel elements, each element having a main body portion and a projecting portion provided with a recess and a heater mounted in said recessed portions.

8. A thermo-electric unit comprising two oppositely disposed thermopiles, each thermopile comprising a series of parallel elements, each element having a main body portion and a projecting recessed portion, said recessed portions being adapted to co-operate with a centrally disposed heater element.

9. In combination, a thermo-electric unit comprising a plurality of substantially flat parallel elements, each element having a recessed portion at one end thereof, said recessed portions cooperating to form a groove at one end of the unit and a second thermo-electric unit having a groove, said units being arranged with their grooves in abutting relation to form a central cavity.

10. In combination a thermo-electric unit comprising series of flat, substantially parallel elements, said unit having a groove at one end thereof, a second thermo-electric unit having a groove at one end and arranged opposite said first unit with the grooves in abutting relation to form a central cavity, and a heater element within said cavity.

11. A plurality of thermo-electric units comprising a series of flat, substantially parallel elements, each unit including a main body portion and a projecting portion, said projecting portion being provided at one end with a groove, said units being arranged opposite one another with their grooved ends in abutting relation to form a central cavity, and a heater element in said cavity.

12. In combination a thermo-electric unit comprising series of flat, substantially parallel elements, said unit having a groove, a second thermo-electric unit having a groove, said units being arranged with their grooves in abutting relation to form a central cavity, a heater element in said cavity, the dimensions of the heater element being substantially equal to the dimensions of said cavity.

13. A thermo-electric unit comprising two oppositely disposed thermopiles, each thermopile comprising a main body portion, a head portion and a reduced portion connecting said head and body portions, a heater disposed between said thermopiles and a heat conserving device substantially surrounding said head portions and heater, and provided with oppositely disposed slots adapted to engage said reduced portions.

14. A thermo-electric unit comprising

- two oppositely disposed thermopiles, each thermopile comprising a main body portion, a head portion and a reduced portion connecting said head and body portions, a heater disposed between said thermopiles, a heat conserving device adapted to slide upon said reduced portions, and to substantially surround said head portions and heater.
15. A thermo-electric unit comprising a thermopile having a head portion provided with a groove, a heater closely fitting within the groove and a reduced portion connected to said head portion.
16. A thermo-electric unit comprising a thermopile having a main body portion and a head portion, said head portion being provided with a groove, an electrically insulated heater closely fitting within the groove and a reduced portion connecting said head and body portion.
17. In combination a thermopile provided with a groove and an electrical heater within said groove, said heater comprising a core of insulating material having a reduced end portion, a metallic ferrule on said reduced portion and a winding on said core and on a portion of said ferrule.
18. In combination a thermopile provided with a groove and an electrical heater closely fitting within said groove, said heater comprising a core of insulating material having reduced end portions, metallic ferrules on said end portions, a winding on said core and ferrules, the turns of said winding being of substantially uniform diameter throughout the entire extent of said winding.

In witness whereof, I have hereunto set my hand this 30th day of March, 1925.

NATHAN H. ADAMS.
